Primary Examiner—Caron D. Veynar*Assistant Examiner*—Ricky Pham*(74) Attorney, Agent, or Firm*—Wolf, Block, Schorr & Solis-Cohen LLP(57) CLAIM

I claim the ornamental design for a utensil surface pattern, as shown and described.

DESCRIPTION

FIG. 1 illustrates a front view of a utensil surface pattern showing my new design;

FIG. 2 illustrates a rear view thereof;

FIG. 3 illustrates a right side view thereof;

FIG. 4 illustrates a left side view thereof;

FIG. 5 illustrates a top plan view thereof; and,

FIG. 6 illustrates a bottom plan view thereof.

The broken line showing of a utensil in FIGS. 1-6 is for illustrative purposes only and forms no part of the claimed design.
